CHARLES SOUTTER, OF BRUNSWICK, VICTORIA, AUSTRALIA.

BRONZING AND DUSTING ATTACHMENT FOR PRINTING AND LITHOGRAPHING MACHINES.

1,149,413.

Specification of Letters Patent. Patented Aug. 10, 1915.

Application filed July 18, 1913. Serial No. 779,673.

To all whom it may concern:

Be it known that I, CHARLES SOUTTER, of 58 Fraser street, Brunswick, in the State of Victoria, Commonwealth of Australia, 5 machinist, have invented certain new and useful Improvements in Bronzing and Dusting Attachments for Printing and Lithographing Machines, of which the following is a specification.

10 This invention relates to an improved bronzing and dusting attachment for cylinder printing and lithographing machines and has for its object the provision of exceedingly simple and easily controlled mech-

15 anism whereby printing in gold and bronze can be expeditiously performed and without allowing the gold or bronze dust to get into the atmosphere in sufficient quantities to injure the health of the operators.

20 Hitherto it has been the custom to do the printing on the ordinary printing or lithographing machine and then while the printing is still damp to take the sheets of paper to a special room in which is placed the 25 bronzing machine. The object in keeping a separate room for bronzing and dusting is to prevent as far as possible the escape of the dust laden air to the atmosphere breathed by the other workmen.

30 The disadvantages of the ordinary method of bronzing and dusting are the necessity of employment of two separate and detached machines, therefore requiring separate operators for each, and labor and time for transferring the printed matter from one machine to the other. Moreover, owing to the bronzing and dusting being done in a confined 35 space the operators inhale a considerable amount of the dust and frequently it is found necessary to work very short hours 40 to enable the operators to guard against the injurious effect of the dust laden air.

Now the object of the present invention is to obviate the abovementioned disadvantages by attaching a simple and easily controlled bronzing and dusting apparatus to the ordinary cylinder printing and lithographing machines in such a way that the paper is printed, bronzed and dusted in one 50 continuous operation, the bronzing and dusting being performed at a uniform rate to the printing.

The said apparatus does not require a separate attendant and it is so constructed

and operated that only a minimum quantity 55 of dust escapes to the atmosphere.

The invention broadly consists in mounting a casing containing the bronzing and dusting apparatus over the feed end of a printing machine and in operating the said 60 apparatus from a rotary shaft on the said machine. The inner end of the casing supports a cylinder having peripherally disposed grippers which take the paper from the flier drum, carry it around past the 65 bronzing rollers thence through a series of dusting rollers to the fliers or to a receiving table.

In order that the invention may be more readily understood reference will now be 70 had to the accompanying sheets of explanatory drawings wherein:—

Figure 1 is a view in side elevation of the improved bronzing and dusting attachment. Fig. 2 is a view in sectional elevation of Fig. 75 1. Fig. 3 is a view in plan of part of the apparatus taken on the dotted line I—I of Fig. 2. Figs. 4 to 13 are views of constructional details hereinafter fully described.

Throughout the drawings similar characters of reference have been employed to indicate like parts in the different views and the numeral 1 designates the casing which is supported in position by brackets 2 bolted to the frame 3 (part only being shown) of 80 85 the printing machine or by other approved means.

The inner end of the casing 1 surrounds a bronzing cylinder 4 the journals of which are mounted in suitable bearings fitted to 90 the sides of the said casing. A spur wheel 5 is carried on one of the journals of the bronzing cylinder and meshes with a pinion 6 fitted to a shaft 7 mounted transversely in the casing thereabove. Motion is im- 95 parted to the bronzing cylinder 4 by chain and sprocket gearing 6¹ or by any other suitable mechanism from any convenient part of the machine. The said spur wheel 5 and pinion 6 have a two to one movement 100 and they can be located on the inside of the casing 1 as shown in the drawings or they can be fitted to the projecting ends of the journal and shaft on the outside of the casing, as preferred. The bronzing cylinder is 105 provided with a longitudinal recess 8 in which is mounted a rocking shaft 9 having a series of grippers 10 fitted thereto. The

said grippers 10 are arranged to open and close to receive a sheet of paper from a flier drum 11 situated above a printing cylinder 12. Both the drum and cylinder are shown 5 diagrammatically in the drawings.

The grippers 10 are opened by means of a cam wheel 13 and lever 14 and are closed by a spring 15 of preferred design. The cam wheel 13 is provided with teeth on its periphery which mesh with the teeth of a pinion 16 one half its diameter fitted concentrically to the end of the bronzing cylinder. The said pinion 16 preferably is one quarter the diameter of the cylinder and the 10 cam wheel is mounted revolvably on a stud 17 fitted to the side of the casing 1 or to a bracket affixed to the same.

The lever 14 is fitted to the end of the rocking shaft 9 and is of bell-crank form 20 having one arm longer than the other. The arms of the lever 14 project tangentially inward and are provided with laterally projecting studs 18 on their outer ends, said studs preferably being furnished with anti-frictional rollers of approved form. The forward arm of the lever 14 is shorter than the rear arm and when the grippers 10 are 25 in position to take the sheet from the flier drum they are opened by the stud on the shorter arm coming into contact with a cam or projection 19 on the cam wheel.

The cam wheel is rotated in an opposite direction to the bronzing cylinder and directly the stud on the short arm of the lever 30 14 moves away from the cam 19 the grippers are forced by the spring 15 to close on the edge of the sheet released from the flyer drum.

The bronzing cylinder has a continuous 40 movement and when the attachment is applied to a printing machine the sheet is taken over the top of the said cylinder and down past bronzing rollers located in the bottom of the casing. The sheet is then carried around until its forward edge is brought to the top of the cylinder where it is released by the stud 18 on the long arm of the lever 14 coming into contact with a cam 21 on the cam wheel 13.

The lever 14 is forced upwardly when it abuts against the cam 21 and the grippers 10 open to permit a second set of grippers 22 carried on endless chains 23 to grip the forward edge of the sheet of paper. The 45 endless chains 23 are carried on sprockets 24 fitted to the transverse shaft 7 and to the ends of a cylinder 25 located transversely in the opposite end of the casing.

The grippers 22 are fitted to a cross rod 26 carried by the chains 23 and the said grippers normally are forced to bear upon a similar rod 27 located at the rear thereof by a spring 27¹ arranged as shown or in any other approved way. The paper released 50 from the bronzing cylinder is gripped be-

tween the grippers 22 and the rod 27 and is carried toward the rear of the casing 1 through a series of oppositely revolving cylindrical brushes 28 having their journaled ends mounted in bearings 29 fitted adjustably by means of bolts or set screws 29¹ to the sides of the casing as shown in Fig. 7 of the drawings.

The brushes 28 are arranged in pairs as shown and the chains 23 pass and carry the sheet between each pair of said brushes to and around the cylinder 25 and then back through a second series of revolving brushes 30 situated in the top of the casing. The brushes 28 and 30 with the exception of the last pair in the top series are arranged to move in an opposite direction to that taken by the paper in order to effectually disperse the bronze or gold dust and remove any unnecessary quantity of the same from the 85 paper. The said brushes are formed of any suitable material covering a wood or other base.

The cylinder 25 keeps the sheet of paper perfectly flat when passing from the lower 90 to the upper series of brushes. The last pair of brushes 30 of the upper series revolve in the direction taken by the paper and assists in feeding it on to endless tapes 31 which direct it to the flyers (not shown) 95 when the said paper is released from the grippers. The said tapes 31 are mounted on revolving rollers or reels 32 of approved form which can be operated in any convenient way.

The end of the rod 26 carrying the grippers 22 is formed with a depending arm 33 to which is fitted a laterally projecting stud 34 preferably carrying an antifrictional roller of approved form. When the grippers 22 have moved over the top of the sprockets 24 the stud 34 on the arm 33 comes into contact with the upper end of a cam-shaped projection 35 fitted to the sides of the casing 1 and this projection causes the 100 rod to be partially rotated to turn the grippers outwardly or a little more than at right angles from the chains. The cam-shaped projection 35 can be fitted adjustably to the side of the casing to permit of it being set 105 at any desired angle. The said grippers are forced to close by the spring 27¹ when the stud 34 passes off the cam-shaped projection 35 and this spring may encircle the gripper rod and have one end fitted to the arm 33 and the opposite end arranged to bear on the rod 27 as shown in Fig. 4 of the drawings.

Simultaneously with the opening of the grippers 22 a fork 36 situated above the shaft 7 is set in motion and moves forwardly to direct the forward edge of the paper over the top of the tapes 31. The said fork is reciprocated by a lever 37—the upper end of which has a slot and pin connection 38 with a lug depending from the side of the said 110

fork—and by a cam 39 formed on or fitted to the journal or end of the bronzing cylinder.

The lever 37 is pivotally mounted on a 5 stud 40 fitted to the side of the casing and its lower end is kept bearing against the cam 39 by a spring 41 which is employed to return the lever 37 and fork 36 to their normal positions after being thrust forwardly 10 by the action of the said cam.

The motions of the chains 23 and bronzing cylinder 4 are timed to bring the grippers 22 into position to take the next sheet of paper from the said cylinder in the manner before described and after it has passed 15 over the bronzing rollers.

If preferred, a lever 37 can be provided at each end of the fork 36 and a cam 39 of each 20 end of the cylinder 4 to insure the said levers operating the fork evenly and uniformly at both ends and it can be mounted in approved forms of guides as 36¹.

The chains 23 and circumference of the bronzing cylinder may be of equal length 25 but the said chains preferably are double the length of the circumference of the cylinder. The chains can be of greater length and fitted with two sets of grippers 22 that are timed to take the sheets from the cylinder 30 and deliver them to the tapes 31 at a uniform rate with the printing operations.

A grooved pulley 42 is fitted to one end of the shaft 7 and a similar pulley 42 is fitted to a projecting end of one of the journals of the cylinder 25 and smaller grooved pulleys 43 are fitted to the projecting journals on the corresponding ends of the revolving brushes 28 and 30. An endless cord or belt 44 is passed around the said pulleys 40 42 and 43 to rotate the brushes 28 and 30 as before described and as shown in Fig. 1 of the drawings while an idle pulley 45 can be mounted adjustably in a suitable position to permit of the tension of the cord or belt 44 being regulated as required.

If preferred, the end of the journal of the bronzing cylinder fitted with the driving sprocket 6¹ can be extended and mounted in a bearing 46 (part only of which is shown) 50 of approved form to insure the said cylinder remaining perfectly horizontal when in operation.

The casing 1 can be detachably and adjustably fitted to the frame of the machine in any other preferred way and not necessarily as hereinbefore described and as shown in the drawings.

The bronzing rollers comprise a slowly 60 revolving or intermittently operated feed roller 47, a distributing roller 48 and two or more revolving brushes 49 which latter are arranged to brush against the surface of the paper lying on the periphery of the cylinder 4.

The feed roller 47 is provided with longi-

tudinally disposed grooves 50 (see Figs. 3 and 12) and operated in a transversely disposed chute or trough 51 fitted to the casing. The said grooves 50 may extend part of or the full length of the roller 47 and they can 70 be arranged parallel with the axis or helically on the periphery thereof. In a modified form of feed roller the grooves 50 can be substituted by circular or other shaped recesses. The said chute or trough 51 is 75 designed to hold the bronzing or gold dust and as the feed roller 47 is revolved the grooves 50 or recesses therein take up a small quantity of the dust and delivers it on to the surface of the distributing roller 80 48 which directs it upon the brushes 49. The said brushes 49 apply the dust evenly on the printed surface of the paper and the superfluous dust is afterward removed by the brushes 28 and 30 as hereinbefore described. The dust can be placed in a hopper 52 fitted to the side of the casing 1 from which it can gravitate into the end of the trough 51 along which it is evenly distributed by an Archimedean screw 53 or the 90 like operated in any preferred way. An intermittent motion can be imparted to the feed roller 47 by affixing a variable throw disk-crank 54 to the projecting end of one of the journals of the bronzing cylinder 4 95 and connecting said disk by a link 55 to a pivoted arm 56 having a pawl 57 arranged to engage a ratchet 58 fitted to the end of a journal of the said roller. By adjusting the throw of the disk-crank 54 the roller 100 can be operated slower or quicker as desired—see Figs. 3 and 13.

The distributing roller 48 and brushes 49 can be operated from a pulley 59 or the like 105 fitted to the shaft 7 by a belt 60, a pulley 61 on the end of a journal of the distributing roller and gear wheels 62 fitted to the opposite journals of the roller and brushes as shown in Figs. 1 and 13 of the drawings.

The casing 1 can be provided with a horizontal partition 63 practically dividing the casing into an upper and lower compartment in which the brushes 30 and 28 respectively operate. The said partition effectually prevents the dust removed from the paper by the top series of brushes 30 falling on to the lower series of brushes 28 and the said partition can be formed in two or more separate parts and inclined so as 115 to direct superfluous dust back to the hopper 52.

It is not essential that the arms of the lever 14 should vary in length as by raising the stud 17 carrying the cam wheel 13 (as 125 shown in Figs. 8 and 9) the arms may be made of equal length to cause the grippers 10 to open and close at their proper times.

In Fig. 8 the bronzing cylinder 4 and the flyer drum 11 are represented by dotted circles and serve to indicate the positions of 130

the lever 14, cam wheel 13 and sprocket wheel 24, respectively therewith. In the last mentioned figure the lever 14 is shown in the position it occupies preparatory to its operation for opening the grippers 10 to take a sheet of paper from the flyer drum and in dotted lines in the position occupied prior to opening to release the sheet.

Figs. 10 and 11 of the drawings illustrate 10 an alternate means of opening the grippers 10 to receive and release the sheet of paper as required. Fig. 11 represents part of the machine in sectional elevation and Fig. 10 is a view in sectional side elevation taken 15 on the dotted line II—II of Fig. 11 and viewed in the direction of the arrow. In the construction illustrated as above set out the rod 9 is provided on one end with a lever 64 having long and short arms 65 and 20 66, respectively. A spring 67 of approved design is employed to retain a constant pressure on the long arm of the lever in order to keep the grippers closed normally. The pinion 6 or the shaft 7 is fitted with two 25 arms 68 and 69 of different lengths which are furnished with laterally projecting studs 70 adapted to contact with the ends of the lever 64 at predetermined times when the machine is in operation.

30 In Fig. 10 the bronzing cylinder is shown in position where the grippers must be opening to take the sheet from the flyer drum—part of which is indicated by a dotted line. The said grippers are caused to open 35 by the stud 70 on the long arm 68 bearing on and depressing the long arm 65 of the lever 64 when the apparatus is in motion. The said stud 70 is arranged to bear upon the arm 65 until the bronzing cylinder 4 is 40 in a position for the grippers 10 to close on the sheet when the stud will—owing to its greater rapidity of movement—pass from and permit the lever to be returned to its normal position by the action of the 45 spring 67.

When the sheet has been taken around past the bronzing rollers or brushes and its forward edge is above the cylinder 4 the stud 70 on the short arm comes into contact with the short arm 66 of the lever 64 and forces it forwardly to open the grippers 10 to release the sheet. The lever 64 is shown in dotted lines in position just prior to it being operated on by the short arm 55 69. Directly the sheet is released from the grippers 10 it is caught by the grippers 22 on the chains 23 and conveyed through the dusting rollers 28 and 30 as before described.

60 In Figs. 10 and 11 the sprockets 24 are shown half the size of the bronzing cylinder 4 and the arms 68 and 69 and lever 64 are shown as adapted to this construction but it will be obvious that by making a slight alteration and adjustment of the lever and

arms the difference between the sizes of the sprockets 24 and the cylinder 4 can be greatly varied without interfering with the proper control of the machine. In some cases it may not be convenient to employ 70 sprockets 24 half the size of the bronzing cylinder 4 and in these instances the sprockets can be made smaller or larger to suit the altered requirements and by introducing intermediate gearing—or back gearing 75 the cam wheel 13—to make the lever 14 and cams 19 and 21 time accurately to open the grippers 10 at correct intervals. The gearing employed to operate the sprocket shaft 7 may also be modified to actuate the 80 chains 23 carrying the grippers 22 at a suitable rate to take the printed sheets from the bronzing drum. The lever 14 or the lever 64 whichever is most suitable can be employed to open the grippers 10 in the 85 modification above described.

In attaching the invention to lithographing machines the lower set of brushes 28 can be dispensed with and the printed and bronzed sheet can be taken from the top of 90 the bronzing cylinder (which together with the sprockets 24 are revolved in an opposite direction to that before described) and then passed through the brushes 30 around the cylinder 25 and delivered to a table or receiving board located beneath the casing. It will be understood that the brushes 30 in this case revolve in an opposite direction to that taken by the sheet and the fork 36 and means for operating it can be dispensed 95 with. The manner of arranging the different parts of the invention to suit the requirements of lithographing machines and different types of printing machines will be readily understood from the foregoing description by a person skilled in the art to which the same relates.

The bronzing apparatus hereinbefore described with slight modifications can be employed independently of a printing machine 110 for bronzing printed sheets of paper and the like and such modifications can be readily effected by any engineer having a knowledge of printing machinery.

While I have described in the foregoing 115 specification the construction of parts and operations preferred I am aware that various modifications may be made in the apparatus without departing from the spirit and scope of the invention, and I, therefore, do not wish to be understood as limiting myself by the exact terms employed in the description, excepting such as the state of 120 the art may require.

What I do claim is:—

1. In a bronzing and dusting apparatus 125 the combination of a cylinder, means on said cylinder to grip a sheet of paper, rollers and brushes for delivering and brushing bronze dust on the paper on said cylinder, 130

- and endless conveyer, means for releasing the paper from the cylinder after a complete revolution and delivering it to the conveyer, means on the conveyer to grip said delivered sheet, a series of pairs of rotary brushes between which the sheet on the conveyer is carried, and means to release the paper gripping means on the conveyer and discharge the sheet, substantially as and for 10 the purpose specified.
2. A bronzing and dusting apparatus comprising in combination, a casing having a bronzing cylinder located in the lower end thereof, grippers on said cylinder, an intermittently operated feed roller disposed in a hopper or trough and having a grooved or recessed periphery, a distributing roller and revolving brushes lying parallelly with said feed roller, an endless conveyer located 15 above and at a tangent to the said cylinder, and revolving brushes operating on both sides of said conveyer.
3. In a bronzing and dusting attachment for printing and lithographing machines, 20 a casing located above the flyer drum or printing cylinder, a bronzing cylinder in one end of said casing and operating adjacent to the flyer drum or printing cylinder, grippers on said bronzing cylinder, a lever and 25 cams for opening and a spring for closing said grippers, bronzing rollers and brushes located near the bottom of the bronzing cylinder, an endless conveyer comprising chains, grippers and sprockets for taking a 30 bronzed sheet of paper from the bronzing cylinder, and revolving dusting brushes located on each side of the said conveyer, substantially as described.
4. In a bronzing and dusting apparatus 35 attachable to printing and lithographing machines the combination of a casing, a bronzing cylinder, bronzing rollers and brushes, grippers on said bronzing cylinder, endless chains operating on sprockets above 40 said bronzing cylinder, oppositely revolving brushes located on each side of said chains and actuated by pulleys and belt, and grippers on said chains all arranged and 45 operating, substantially as described and substantially as illustrated and for the purposes set forth.
5. In a bronzing and dusting apparatus 50 attachable to printing and lithographing machines, a casing having a bronzing cylinder, rollers and brushes at one end, grippers on said cylinder, sprockets fitted to a shaft located above the cylinder and sprockets situated in the opposite end of said casing, endless chains passing around said 55 sprockets, spring actuated gripping members fitted to a rod carried by said chains, said grippers bearing on an adjacent and similarly disposed rod, an arm on one end of the gripper carrying rod, and a fixed cam-shaped plate or projection disposed in 60 the path of the said arm, substantially as described.
6. In a bronzing and dusting apparatus attachable to printing and lithographing machines the combination of a casing, a bronzing cylinder located transversely in 65 one end of said casing, a bronze containing trough or hopper adjacent to said cylinder, means for keeping the bronze at an even depth throughout the length of the trough or hopper, a feed roller having a recessed periphery and operated intermittently in 70 said trough or hopper, a continuously revolving distributing roller disposed parallelly with and adjacent to said feed roller, and revolving brushes bearing against the 75 periphery of said cylinder, substantially as described and illustrated and for the purposes set forth.
7. In a bronzing and dusting apparatus for printing and lithographing machines, 80 the combination of a bronze containing trough or hopper and a feed roller having a grooved or recessed periphery operating intermittently in said trough, substantially as described and for the purposes set forth.
8. In a bronzing and dusting apparatus 85 for printing and lithographing machines, the combination of a bronze containing trough or hopper, a feed roller having a grooved or recessed periphery operating intermittently in said trough, and a screw operating in said trough for evenly distributing the bronze dust, substantially as described and for the purposes set forth.
9. In a bronzing and dusting attachment 90 for printing and lithographing machines, the combination of a bronzing cylinder having a longitudinal recess therein, a rocking shaft in said recess, a bell-crank lever fitted to one end of said shaft, studs on the 95 ends of said lever, a pinion fitted concentrically to the end of the cylinder, a gear meshing with said pinion, cams on said gear for operating said lever to open the grippers, and a spring to close said grippers, substantially as described and for the purposes set forth.
10. In a bronzing and dusting attachment 100 for printing and lithographing machines the combination of a bronzing cylinder having peripherally disposed means for gripping the edge of a sheet of paper, rollers 105 and brushes for delivering and brushing bronze dust on said paper, a pair of endless chains mounted on sprockets fitted to cross shafts, a pinion on one of said cross shafts meshing with a spur wheel fitted to the cylinder, a driving sprocket fitted to a spindle 110 of said cylinder, paper grippers on said chains and oppositely revolving brushes for 115 dusting the paper carried by the grippers on the chains, substantially as described and for the purposes set forth.

11. In a bronzing and dusting apparatus for attachment to printing and lithographing machines, the combination of a bronzing cylinder having a longitudinal recess there-
5 in, a rocking shaft in said recess, grippers on said shaft, a lever on one end of said shaft having a long and a short arm, arms of unequal length fitted to a revolving wheel or shaft, studs on said arms adapted to contact with and actuate the long and short arms of said lever and a spring acting on the long arm of the lever to keep the grippers tightly closed, substantially as described and for the purposes set forth.
- 15 12. In a bronzing and dusting attachment for printing and lithographing machines, endless chains operating on sprockets fitted to a shaft and cylinder, grippers on said chains to take a sheet of paper from a bronzing cylinder, adjustably mounted revolving brushes arranged on both sides of said chains, and a reciprocatingly mounted fork for directing the forward end of the paper on to delivery tapes when released from the 25 chain grippers, substantially as described and for the purposes set forth.
13. In a bronzing and dusting attachment for printing and lithographing machines, the combination of a bronzing cylinder having paper grippers thereon, bronzing rollers and brushes adjacent to said cylinder, endless chains operating at a tangent to said cylinder and having paper gripping devices extending from one chain to another, and 30 revolving brushes arranged in series and operating on both sides of the paper carried by the chains and in an opposite direction thereto, substantially as described and for the purposes herein set forth.
- 40 14. In a bronzing and dusting attachment for printing and lithographing machines the combination of a bronzing cylinder having a longitudinal recess therein, a rocking shaft in said recess, grippers on said shaft, a lever fitted to one end of said shaft and actuated by movable cams, and a spring keeping a constant closing pressure on said grippers, substantially as described and for the purposes set forth.
- 45 50 15. In a bronzing and dusting apparatus attachable to printing and lithographing machines, the combination of a casing, a bronzing cylinder having means to grip a sheet of paper, rollers and brushes for delivering and brushing bronze dust on the 50 paper on the cylinder, endless sprocket chains operating in a plane above the bronzing cylinder, oppositely revolving brushes located at opposite sides of said chains, grippers on said chains to grip a sheet of paper 60 delivered from the cylinder, a reciprocable fork to release said latter grippers, a pivotal lever for actuating said fork, and cams for actuating said lever, substantially as and for the purpose specified.
- 65 16. In a bronzing and dusting apparatus attachable to printing and lithographing machines, the combination of a casing, a bronzing cylinder located in one end of said casing, a bronze containing trough adjacent to said cylinder, means for keeping the bronze at an even depth throughout the length of the trough, a feed roller having a recessed periphery and operated intermittently in said trough, a continuously revolving distributing roller parallel with and adjacent to said feed roller, revolving brushes bearing against the periphery of said cylinder, a variable throw eccentric on a journal of the bronzing cylinder, a pivoted arm, a link connecting said eccentric to said arm, a pawl on said arm, and a ratchet fitted to a journal of the feed roller, substantially as and for the purpose set forth.
- 70 75 17. In a bronzing and dusting attachment for printing and lithographing machines, the combination of a bronzing cylinder having a longitudinal recess therein, a rocking shaft in said recess, a bell-crank lever fitted to one end of said shaft, studs on the ends of 80 said lever, a rotatable cam wheel, a pinion gearing with said wheel and fitted concentrically to the end of said cylinder for operating said lever to open the grippers, and a spring to close said grippers, substantially 90 as and for the purpose set forth.
- 85 90 95 In witness whereof I have signed this specification in the presence of two witnesses.

CHARLES SOUTTER.
